UNITED STATES PATENT OFFICE.

GEORGE J. SHIMER AND SAMUEL J. SHIMER, OF MILTON, PENNSYLVANIA.

TOOL FOR DRESSING AND TURNING EMERY-WHEELS.

SPECIFICATION forming part of Letters Patent No. 240,279, dated April 19, 1881.

Application filed March 5, 1881. (Model.)

To all whom it may concern:

Be it known that we, GEORGE J. SHIMER and SAMUEL J. SHIMER, citizens of the United States of America, residing at Milton, in the county of Northumberland and State of Pennsylvania, have invented certain new and useful Improvements in Tools for Dressing and Turning Emery and Similar Wheels; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has relation to tools for "truing" and turning emery-wheels.

Our invention consists in a metallic bar having a longitudinal channel or groove formed therein, capable of receiving two or more steel-plate springs to serve the office of cutters.

Our invention also consists in a metallic bar having a channel formed therein to receive two or more steel-plate spring-cutters, and a sleeve fitting the bar over the spring-cutters, and a set-screw in the sleeve to secure and clamp the spring-cutters in position for use.

Our invention further consists in a transparent shield set in the upper part of the sleeve, to act as a protection to the eyes of the operator and to afford unobstructed vision in the turning of the stone.

Our invention further consists in the combination, with a metallic bar provided with a longitudinal channel and two or more steel springs, of a sleeve provided with a set-screw.

Our invention further consists in the combination, with a metallic bar provided with a longitudinal channel to receive two or more steel springs, and a sleeve provided with a set-screw, of a diagonal slot and a transparent shield.

In the accompanying drawings, Figure 1 is a perspective view of the tool, showing the mode of operation. Fig. 2 is a perspective view of the tool complete. Fig. 3 is a perspective view of the adjustable sleeve. Fig. 4 is a perspective view of one of the steel bars constituting a cutter, and Fig. 5 is a front view of the transparent shield.

In the accompanying drawings, the letter A represents a metallic bar, having formed therein the longitudinal channel or groove *a*, intended to receive two or more cutters consisting of steel-plate springs, as seen in Fig. 2 of the drawings.

The letter B represents the adjustable sleeve, which fits over the bar A and secures the plates forming the cutters in position. This adjustable sleeve is preferably of the shape shown in Fig. 3 of the drawings, and is provided with legs serving as rests for the tool when in operation, as seen in Fig. 1 of the drawings.

The letter C (see Fig. 4) represents a plate or bar spring of steel, made of such width as to fit in the longitudinal channel or groove of the bar. Two or more of these plates are placed together in the channel, as shown in Fig. 2 of the drawings, wherein they are confined at their forward parts by means of the adjustable sleeve provided with the set-screw. The set-screw *b* in the upper part of the adjustable sleeve passes through the metal of the sleeve and screws down on the bar-springs, thus clamping them firmly in the channel and together.

The letter *c* indicates a diagonal slot cut in the sleeve, and in it is fitted the transparent shield D. (See Fig. 5.) The object of the shield is to protect the operator's face and eyes from the flying particles of emery and stone during the process of dressing the wheel, and at the same time enable him to see the progress of the work. This shield is preferably of mica, and has at its base a metal strip to strengthen it at that part, and to prevent it from flaking or being otherwise injured in putting it in position.

The channeled bar has an ordinary tool-handle attachment, or it may be made with the handle forming an integral part of the bar.

It will be observed that the plates of steel are secured against lateral displacement by the side walls of the channel of the bar, and are secured against undue vibration by the sleeve and the downward pressure of its set-screw.

The tool in its several parts having been described, the mode of adjusting and uniting them for use is readily understood. The adjustable sleeve with set-screw drawn above the

upper wall of the passage is passed over the metallic bar from its forward end, and the steel bars are then run under the sleeve, and when in position they are clamped firmly in place with the set-screw. The transparent shield is then adjusted in the diagonal slot of the sleeve. The adjustment of the parts may be varied by first placing the steel bars in the channel of the metallic bar and then passing the sleeve over them and the bar and securing the bar-springs, as stated hereinbefore. The steel bars are arranged and adjusted at their forward or cutting ends so that the uppermost shall be advanced in the direction of the emery-wheel farther than its mate beneath, and this, in turn, also advanced farther in same direction than its mate beneath, and so on to the last. This is substantially shown in Fig. 2 of the drawings. The object of this gradual recession from top to bottom plate is that each spring shall present a cutting or picking edge to the surface of the wheel.

The operation is accomplished by holding the tool, like an ordinary turning-tool, a little above the center of the emery-wheel, (see Fig. 1,) so that the steel springs will vibrate, when, instead of being ground away by the wheel, they "pick" against the face of the wheel and turn it off, each spring acting in the nature of a small mill-pick driven at a very high speed.

In practice it will be found that the springs are worn away very slowly.

In turning very hard and compact wheels, the steel cutters or pickers are set closer to the forward end of the channel than when soft wheels are turned or dressed. For "soft or ten" wheels the steels are set about one-half inch beyond the end of the bar and the set-screw about two and a half inches back.

The tool can also be used to take the glaze off of the "hard close" wheels, in which operation it is the better plan to rest the tool on the hand, and not to let it touch the solid rest.

It is obvious that the groove or channel in the bar may be dispensed with, and the steel spring-cutters rest on the flat top of the bar and retained in this position by means of the top and side walls of the sleeve.

We do not wish to confine ourselves to the precise construction herein described and shown, as changes may be made without departing from the spirit of the invention.

What we claim as our invention, and desire to secure by Letters Patent, is—

1. In a hand-tool for truing and turning emery and similar wheels, the metallic bar provided or formed with a longitudinal channel or groove to receive two or more steel-plate spring-cutters.

2. In a hand-tool for truing or turning emery or similar wheels, the combination of a metallic bar, two or more spring bar cutters, and a holding-sleeve, substantially as described.

3. In a hand-tool for truing and turning emery and similar wheels, the combination of the metallic bar formed with a longitudinal channel or groove, two or more spring bar cutters fitting within said groove, and a holding-sleeve, substantially as described.

4. In a hand-tool for truing and turning emery and similar wheels, the combination of a metallic bar formed with a longitudinal channel or groove, with two or more spring bar cutters arranged therein, and an adjustable sleeve with a set-screw, substantially as described.

5. In a hand-tool for truing and turning emery and similar wheels, the combination of a metallic bar formed with a longitudinal channel or groove, with two or more spring bar cutters arranged therein, a sleeve, and a transparent shield.

6. In a hand-tool for truing and turning emery and similar wheels, the combination of a metallic bar formed with a longitudinal channel or groove, with two or more spring bar cutters arranged therein, and an adjustable sleeve with a set-screw, and a transparent shield, substantially as described.

7. As a new article of manufacture, a mica transparent shield having a metallic binding-edge, for the purpose set forth.

8. In a hand-tool for truing and turning emery and similar wheels, the sleeve capable of a sliding or adjustable movement, and formed with a diagonal slot to receive a transparent shield, and provided with a set-screw, substantially as described.

In testimony whereof we affix our signatures in presence of two witnesses.
